UNITED STATES PATENT OFFICE

CHARLES E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY

SEWING MACHINE

Application filed May 12, 1928. Serial No. 277,113.

The invention relates to sewing machines and is herein disclosed as embodied in a lockstitch outsole shoe sewing machine employing a curved hook needle.

The primary object of the invention is to provide a novel and improved mechanism for handling thread in a lockstitch machine which is particularly adapted for use in a leather sewing machine of this general description to secure an even stitch with each lock set at the same distance into the work.

With this object in view, the principal feature of the invention consists in the provision of mechanism which acts to pull the needle loop down to a predetermined point, with relation to the surface of the work, preferably in close proximity thereto, and then acts to draw the loop down a predetermined amount from this point to set the stitch a uniform distance into the work.

As herein disclosed in a lockstitch outsole shoe sewing machine, the needle loop is pulled down by a constant throw take-up lever operating against a tension until the loop is engaged and held by a loop detaining finger associated with the presser foot a predetermined distance above the surface of the work while the continued operation of the take-up acts to draw off from the supply the amount of thread required for the next succeeding stitch. The loop is drawn down from the point where it is held by the loop detaining finger to set the stitch in the work by means of a constant throw auxiliary take-up operating against a thread lock so that a uniform stitch is obtained with the lock a uniform distance into the work. The mechanism described is simple in construction, requiring no separate thread measuring mechanism or any elaborate adjustment of the take-up mechanism in accordance with the thickness of the work, and is at the same time extremely accurate and efficient in operation, making possible the formation of an even regular seam in which the locks are all placed at a uniform distance below the surface of the work.

To further insure the formation of regular even stitches, a small abutment is formed on the presser foot and is adapted during the

relative feeding movements of the presser foot and the work to draw thread from the bobbin and lay a section of bobbin or locking thread along the surface of the work preparatory to the formation of the next stitch. The locking thread is thus measured accurately regardless of the length of stitch and the needle loop, as it is pulled down, falls naturally into the bight thus formed in the locking thread to set the stitch with a minimum of strain and wear on the threads. Also the production of uniformly tight stitches on both surfaces of the work is insured.

Cooperating with this means for measuring the bobbin thread in accordance with the length of the stitch, a pull off device is provided for pulling an additional amount of thread from the bobbin to enable the lock to be pulled or set the desired distance into the work without breaking the bobbin thread.

The several features of the invention consist also in the devices, combinations and arrangement of parts hereinafter described and claimed and together with the advantages to be obtained thereby should be readily understood by one skilled in the art from the following description taken in connection with the accompanying drawings which illustrate one embodiment of the invention in a lockstitch shoe sewing machine. Fig. 1 is a view in front elevation of the machine illustrating particularly the thread handling devices and certain of their operating connections, only so much of the machine being illustrated as is necessary to show the connection of the present invention therewith; Fig. 2 is a view in left side elevation of substantially the same parts as are shown in Fig. 1; Fig. 3 is a detail view taken on the line 3—3 of Fig. 1; Fig. 4 is a detail sectional view taken on the line 4—4 of Fig. 3; Figs. 5 to 12 are detail views of the sewing elements in front and side elevation at different points in the sewing cycle; Fig. 13 is a view of the seam with the last stitch completed; Fig. 14 is a detail view in side elevation of the bobbin case and the loop taker; and Fig. 15 is a sectional view taken on the line 15—15 of Fig. 14.

The invention is herein disclosed as embodied in a lockstitch shoe sewing machine having except as hereinafter described a construction and mode of operation substantially similar to the machine disclosed in the patent to Ashworth, No. 1,169,909 dated February 1, 1916. A curved hook needle of ordinary construction is indicated at 20, the curved awl cooperating therewith at 22, the work support at 24, the presser foot at 26, the bobbin case at 27, and a loop taker at 28. These parts are actuated from the shafts 30 and 32 of the machine through connections which are more fully described in the patent to Ashworth above referred to.

The needle thread passes from the thread supply through a thread tension 33 of any ordinary construction over the pulley 34 shown in dotted lines in Fig. 2, around the pulley 36 mounted on the take-up lever 37 which is actuated from the shaft 30, and thence upwardly to the work. Inasmuch as these parts may be of any ordinary construction and are in a preferred form fully described and illustrated in the patent to Ashworth above referred to, further illustration thereof is believed unnecessary for a full disclosure of the present invention.

The auxiliary take-up lever 38, the thread clamp 40, and the loop detaining finger 42 are actuated through connections hereinafter to be described from a cam shaft 44 which is driven from the shaft 32 through the gear 46 mounted on the shaft 32 and the intermeshing gear 48 mounted on the shaft 44. The shaft 32 is in turn driven from the shaft 30 through a gear 50 which meshes with the gear 46.

The loop detaining finger 42 is pivotally mounted at 52 on the presser foot 26 so that this finger is adjusted automatically in accordance with the thickness of the work to hold the needle loop a predetermined distance above the surface of the stock being operated upon. The finger 42 is provided with an upwardly extending arm 53 which carries a cam roll 54 engaging in a corresponding slot 56 formed in one end of an actuating lever 58 which is secured to a rock shaft 60 mounted in a fixed bracket 62. The rock shaft 60 is also provided with a cam lever 64 which carries a cam roll 66 adapted to engage a cam 68 on the cam shaft 44 so that the loop detaining finger is given one oscillation for each revolution of the main cam shaft to engage at the proper point in the cycle of operations with the needle loop. Due to the cam and slot connection between the loop detaining finger 42 and its actuating lever 58, the lever is free to move up and down with the presser foot.

In order to avoid any unnecessary stretching of the thread in pulling the loop of needle thread down into the work, with the consequent irregularities and imperfections

in the formation of the seam, the auxiliary take-up and the thread clamp are mounted to operate as close to the work as possible so that the amount of thread acted upon by these parts in setting the stitch is reduced to a minimum. To this end, the thread clamp is mounted to operate on the thread between the constant throw take-up and the work and the auxiliary take-up is mounted to engage the thread between the thread clamp and the under surface of the work.

The auxiliary take-up 38 comprises a short lever arm which carries a pulley 70 which cooperates with a stationary pulley 72. The auxiliary take-up 38 is loosely mounted to turn on a fixed shaft 74, and is also provided with a second arm 76 which is connected through a link 78 with one arm of a bell crank lever 80 loosely sleeved to a rock shaft 82. The free arm of the bell crank lever 80 is in turn connected by means of a link 84 to one arm of a bell crank lever 86 on the fixed pivot 87 which carries on its free arm a cam roll 88 adapted to engage with a cam 90 on the cam shaft 44. A tension spring 91 acts to hold the lever 86 and the roll 88 in contact with the cam 90. The throw of the auxiliary take-up is conveniently adjusted by means of a pin and slot connection 92 of ordinary construction between the link 78 and the bell crank 80.

The thread clamp 40 comprises a lever arm which is loosely mounted on the shaft 74 and is provided with a clamping jaw 94 which cooperates with a corresponding stationary jaw 96 to clamp the thread securely against movement. The thread clamp 40 is actuated from the cam shaft 44 through connections which include an arm 98 which is pivotally mounted on the shaft 74 and is connected to turn with the thread clamp 40 through a yoke 100. A yielding connection is provided between the arm 98 and an arm 102 secured to the rock shaft 82 which comprises a plunger 104 secured to the arm 98 and adapted to fit within a corresponding sleeve member 106 pivotally secured to the arm 102. The sleeve member 106 is also fitted with a compression spring 108 which tends to force the plunger inwardly. The rock shaft 82 is also provided with an arm 110 which is connected by a link 112 with a lever 114. This lever is loosely mounted on the fixed pivot 87 and carries a roll 116 which is held yieldingly in engagement with a cam 118 on the cam shaft 44 by means of a compression spring 119.

Mechanism is also provided which is adapted to pull off thread from the bobbin and lay it along the surface of the work in position so that when the needle loop is pulled down the stitch is set with a minimum of strain on the threads. This mechanism comprises an abutment 120 formed on the presser foot which is adapted during the feed

ing movement of the work to engage with the bobbin thread to pull off the requisite amount from the supply and lay it along the surface of the work to the point where the 5 awl enters the work preparatory to forming a new stitch.

A pull-off is also provided for the locking thread to insure that the required amount of thread is provided for each stitch, and comprises a projecting portion 122 formed on the loop taker 28 which with the present construction is adapted to make three revolutions for each sewing cycle. The pull-off is rendered active to pull off additional thread 10 from the bobbin when the locking thread is held taut between the bobbin case and the work at a point in the sewing cycle directly after the needle loop has been cast about the bobbin by the loop taker. As the pull-off 122 15 comes into contact with the locking thread at this point and acts to force it aside, additional thread is drawn from the supply.

Inasmuch as the amount of locking thread required for each stitch must vary with the 20 distance to which the lock is set in the work, means are provided for adjusting the amount of locking thread pulled off to correspond with the adjustment of the auxiliary take-up lever. Four guide holes indicated at 126 for 25 the locking thread are provided in the bobbin case set at intervals so that the locking thread when stretched between each of these holes and the work will be moved aside by the pull-off varying amounts to cause different 30 amounts of thread to be drawn from the bobbin. In this manner, four different adjustments of the pull-off for the locking thread can be obtained which correspond to the 35 different adjustments of the auxiliary take-up lever.

The operation of the thread handling mechanism above described follows:—Starting with the parts in the positions illustrated in Figs. 5 and 6, after the work has been fed 40 forward preparatory to the forming of a new stitch and the requisite amount of thread has been pulled off from the bobbin and laid along the surface of the work by the abutment 45 above described, the needle now descends to cause a new loop to be brought up through the work and passed around the bobbin, as 50 illustrated in dotted lines in Figs. 7 and 8. In this position of the parts, the loop detaining finger 42 is in its retracted position. As 55 the needle loop is drawn down by the action of the take-up 36, the loop detaining finger is moved forward to engage within the loop of the needle thread so that the loop is detained by the finger a predetermined distance 60 above the surface of the work while the continued movement of the take-up causes the requisite amount of thread for the next stitch to be drawn off from the supply through the thread tension. The parts at this point in the 65 operation are in the positions illustrated in

Figs. 11 and 12. Finally, the thread detaining finger 42 is withdrawn, the thread lock 40 is operated to lock the thread, and the auxiliary take-up 38 is oscillated to finally set the stitch as shown in Fig. 13.

The nature and scope of the invention having been indicated and one embodiment thereof described, what is claimed is:

1. A lockstitch sewing machine having, in combination, a hook needle, a loop taker for 75 passing the needle thread around the bobbin thread, a work support, a thread take-up for drawing down the needle loop after it has passed over the bobbin thread, a loop detaining finger adapted to engage with the needle loop a predetermined distance above the surface of the work, and an auxiliary take-up for setting the stitch in the work prior to the formation of the next needle loop.

2. A lockstitch sewing machine having, in combination, a hook needle, a loop taker for 80 passing the needle thread around the bobbin thread, a work support, a thread take-up for drawing down the needle loop, a loop detaining finger against which the needle loop is 85 drawn by the take-up to form a loop of predetermined length above the surface of the work, and an auxiliary take-up for setting the stitch in the work prior to the formation of the next needle loop.

3. A lockstitch sewing machine having, in combination, a hook needle, a loop taker for 90 passing the needle thread around the bobbin thread, a work support, means for passing a needle loop around the bobbin thread, a 100 thread take-up for drawing down the needle loop, a loop detaining finger against which the needle loop is drawn by the take-up to form a loop of predetermined length above the surface of the work, a thread lock, and an 105 auxiliary take-up cooperating with the thread lock to set the stitch in the work prior to the formation of the next loop.

4. A lockstitch sewing machine having, in combination, a hook needle, a loop taker for 110 passing the needle thread around the bobbin thread, a work support, a thread tension, a 115 thread take-up for drawing down the needle loop against the thread tension after passing over the bobbin thread, a loop detaining finger against which the needle loop is drawn by the take-up to form a loop of predetermined length above the surface of the work, a thread lock, and an auxiliary take-up cooperating therewith to set the stitch in the work 120 prior to the formation of the next needle loop.

5. A lockstitch sewing machine having, in combination, a hook needle, a loop taker for 125 passing the needle thread around the bobbin thread, a work support, a presser foot, a take-up for drawing down the needle loop after passing over the bobbin thread, a loop detaining finger supported on the presser foot to engage with the needle loop a predetermined distance above the surface of the work, and

means having a constant throw for setting the stitch in the work.

6. A lockstitch sewing machine having, in combination, a hook needle, a loop taker for passing the needle thread around the bobbin thread, a work support, a presser foot, a thread tension, a thread take-up for drawing down the needle loop against the tension after passing over the bobbin thread, a loop detaining finger mounted on the presser foot to engage the needle loop a predetermined distance above the work, a thread lock, and an auxiliary take-up having a constant throw cooperating therewith to set the stitch in the work.

15. A lockstitch sewing machine having, in combination, a hook needle, a loop taker for passing the needle thread around the bobbin thread, a work support, a thread take-up for drawing down the needle loop, means for detaining the needle loop against the action of the take-up a predetermined distance above the work, and a constant throw auxiliary take-up for setting the stitch in the work prior to the formation of the next needle loop.

25. A lockstitch sewing machine having, in combination, a hook needle, a loop taker for passing the needle thread around the bobbin thread, a work support, a thread tension, a thread take-up for drawing down the needle loop against the tension, means for detaining the needle loop against the action of the take-up a predetermined distance above the work, a thread lock, and a constant throw auxiliary take-up cooperating therewith for setting the stitch in the work prior to the formation of the next needle loop.

35. A lockstitch sewing machine having, in combination, a hook needle, a loop taker for passing the needle thread around the bobbin thread, a work support, a presser foot, a thread tension, a loop detaining finger mounted on the presser foot, a thread take-up for drawing down the needle loop after passing over the bobbin thread against the tension into contact with the loop detaining finger and thereafter for pulling off thread from the supply through the tension for the next stitch, a thread lock, and an auxiliary take-up having a constant throw cooperating therewith to set the stitch in the work.

45. A lockstitch sewing machine having, in combination, a hook needle, a loop taker for passing the needle thread around the bobbin thread, a work support, a thread tension, means adapted to engage with the needle loop a predetermined distance above the work, a thread take-up for drawing down the needle loop against the tension into contact with the loop engaging means and thereafter for drawing additional thread through the tension from the supply for the next stitch, a thread lock, and means cooperating therewith for pulling down the loop a predetermined amount to set the stitch in the work.

11. A lockstitch sewing machine having, in combination, a hook needle, a loop taker for passing the needle thread around the bobbin thread, a work support, a presser foot, an abutment on the presser foot rendered operative by the relative movement of the work and to the presser foot in feeding the work to draw off bobbin thread for the next succeeding stitch, and means for drawing down the needle loop after passing over the bobbin thread to set the stitch.

12. A lockstitch sewing machine having, in combination, a hook needle, a loop taker for passing the needle thread around the bobbin thread, a work support, a presser foot, an abutment on the presser foot rendered operative by the relative movement of the presser foot and the work to draw off bobbin thread, a thread tension, a thread take-up for drawing down the needle loop against the tension, a loop detaining finger on the presser foot for engaging the needle loop a predetermined distance above the work, a thread lock, and a constant throw auxiliary take-up cooperating therewith to set the stitch in the work.

13. A lockstitch sewing machine having, in combination, a hook needle, a loop taker for passing the needle thread around the bobbin thread, a thread tension, a thread take-up acting against the tension to draw down the needle loop to a predetermined point with relation to the surface of the work and thereafter to draw thread through the tension from the supply for the next stitch, a thread lock, and means for thereafter setting the stitch against the thread lock.

14. A lockstitch shoe sewing machine having, in combination, stitch forming and setting devices including a hook needle, a thread tension, means for drawing down the needle loop against the tension until the resistance to the further movement of the loop exceeds the resistance offered by the tension, and thereafter for drawing off additional thread through the tension from the thread supply, and a thread lock against which the stitch is set.

15. A lockstitch sewing machine having, in combination, stitch forming devices including a hook needle, a thread tension, means for pulling on the thread to draw down the needle loop until the resistance to the further movement of the loop exceeds the resistance offered by the tension, then to draw thread from the supply for the next stitch, and finally to set the stitch, and a thread lock cooperating with said thread pulling means to set the stitch a uniform distance into the work.

16. A lockstitch shoe sewing machine having, in combination, stitch forming and setting devices including a hook needle, a thread tension, a take-up for drawing down the needle loop against the tension until the

resistance to the further movement of the loop exceeds the resistance offered by the tension, a thread lock mounted to operate upon the thread between the take-up and the work, 5 and an auxiliary take-up operating upon the thread between the lock and the work to set the stitch against the lock.

17. A lockstitch shoe sewing machine having, in combination, stitch forming and setting devices including a hook needle, a thread tension, a constant throw take-up for drawing down the needle loop against the tension until the resistance to the further movement of the loop exceeds the resistance offered by the tension, a thread lock mounted to operate upon the thread between the constant throw take-up and the work, and a constant throw auxiliary take-up operating upon the thread between the lock and the work 20 to set the stitch against the lock.

18. A lockstitch sewing machine having, in combination, stitch forming and setting devices including a hook needle, a container for the bobbin thread, a loop taker adapted to engage the bobbin thread between the container and the work to pull off additional bobbin thread, and a series of guide holes through which the thread may be passed to vary the amount of thread pulled off from 25 the container by the loop taker.

19. A lockstitch sewing machine having, in combination, stitch forming and setting devices including a hook needle, a container for the bobbin thread, a presser foot, a member on the presser foot adapted to draw off and lay bobbin thread along the surface of the work, and a pull-off device adapted to engage the bobbin thread between the container and the work to pull off additional bobbin 35 thread.

20. A lockstitch sewing machine having, in combination, stitch forming and setting devices including a hook needle, a container for the bobbin thread, a presser foot, a member thereon adapted to draw off and lay along the surface of the work bobbin thread for the next stitch, a pull-off device adapted to engage the bobbin thread between the container and the work to pull off additional 40 bobbin thread, a take-up for setting the stitch adjustable to vary the distance the lock is set into the work, and means for varying the amount of bobbin thread pulled off in accordance with the said adjustment.

55 In testimony whereof I have signed my name to this specification.

ERASTUS E. WINKLEY.
